John L. Mason
Mass. Street, Lawrence

UNITED STATES PATENT OFFICE.

JOHN L. MASON, OF NEW YORK, N. Y.

IMPROVED FRUIT-JAR.

Specification forming part of Letters Patent No. 86,090, dated January 19, 1869.

To all whom it may concern:

Be it known that I, JOHN L. MASON, of the city, county, and State of New York, have invented a new and useful Improvement in Preserve-Jars; and I do hereby declare that the following is a full, clear, and exact description thereof, reference being had to the accompanying drawings, making a part of this specification, in which—

Figure 1 is a view of the improved jar with its cover secured in place. Fig. 2 shows the jar without its cover, but with a gasket or packing-band applied around its rib or flange. Fig. 3 is an enlarged diametrical section through the upper portion of the improved jar, its cover, gasket or packing-band, and band-fastening.

Similar letters of reference indicate corresponding parts in the several figures.

This invention relates to a new and improved mode of hermetically sealing covers upon jars or other vessels which are chiefly designed for preserving fruits, chemicals, and other substances which are decomposed or otherwise injured by exposure to the air.

My invention consists in providing for the use of an elastic india-rubber band for confining a cover in place upon the mouth of a jar or other vessel when such jar or vessel and cover are adapted for receiving a packing-ring, which will afford a tightly-sealed joint without being exposed to the contents of such jar or vessel, as will be hereinafter explained.

To enable others skilled in the art to understand my invention, I will describe its construction and operation.

In the accompanying drawings, A represents a jar, and B its cover, which I prefer to make of glass or other vitreous substances. Near the upper end or mouth of the jar A a wide bead or flange, a, is formed, which encircles the jar and presents a flat upper surface for receiving upon it the lower flanged edge e of the rim d of cover B, as shown in Fig. 3. Rising from this bead or flange a is an annular-beveled rib or flange, b, which surrounds the mouth of the jar A, and is tapered upwardly, as shown in Figs. 2 and 3, for the purpose of receiving upon it a packing, c, made of india-rubber or other suitable material.

B is the cover of the jar, which is cup-shaped, with a flaring rim, d, having an external annular flange or bead, e, formed on its lower edge. This cover B is slightly larger in

diameter internally than the diameter of the tapering rib or flange b, as shown in Fig. 3, so as to receive between it and the external surface of the said rib or flange a packing-ring, c.

The diameter of the flange or bead e externally is equal, or nearly so, to the diameter of the flange b on the jar, and when the cover B is pressed in its place upon the jar it is confined thereon by means of an elastic india-rubber band, g, of suitable width to embrace the two annular projections a and e when stretched over and allowed to contract thereon, as shown in Figs. 1 and 3.

The band g, when thus applied, not only serves to confine the cover B down tightly upon the gasket or packing c, but it also serves as auxiliary to the said packing or hermetically sealing the joint.

The top of the cover B may be made flat, or with a raised annular head, to serve as a foot when the cover is inserted. The bottom of this cover has an annular groove, i, formed in it for receiving the upper edge of the rib or flange b and forming a depression or stopple, f, as shown in Fig. 3.

By this invention I dispense with the use of screw-fastenings, metallic clamps, and other similar fastenings which have been heretofore used for holding covers on preserve-jars, and employ in their stead a simple band of india-rubber stretched over the parts e and a, which will keep the cover B down snugly upon the packing c, and also close tightly the joint between e and a.

I am aware that stopples or covers differing from the flanged cover B have been confined upon vessels by a band of elastic rubber, and therefore I do not claim as my invention the feature alone.

I am also aware that a cover made with an external flange upon its rim is not new; and therefore I do not claim these elements when separately considered.

What I claim as new, and desire to secure by Letters Patent, is—

A jar, A, constructed with an annular bead, a, and upwardly-tapering gasket-receiving rib or flange b, in combination with the flanged cover B d e, packing c, and an elastic band-fastening, g, applied substantially as described.

JOHN L. MASON.
